CONVEYER

Albert Francis White, Toronto, Ontario, Canada,
assignor to Chain Belt Company, Milwaukee,
Wis., a corporation of Wisconsin

Application February 27, 1941, Serial No. 380,884

8 Claims. (Cl. 198—170)

This invention relates to conveyors and more particularly to those having flights moving in closed conduits for conveying grain and other bulk material that can be poured. The object of the present invention is to devise simple and inexpensive means for causing all the material to be completely cleared from the flights when they reach the point of discharge.

The invention is hereinafter more fully described and is illustrated by way of example in the accompanying drawing in which

Fig. 1 is a side elevation partly in section of my improved conveyor;

Fig. 2 a front elevation of the same, partly broken away;

Fig. 3 a detail in side elevation, on an enlarged scale, of part of the chain showing a flight connected therewith;

Fig. 4 a front view of the parts in Fig. 3; and

Fig. 5 a plan of the parts in Fig. 3.

In the drawing like numerals of reference indicate corresponding parts in the different figures.

The conveyor comprises a casing and an endless draft mechanism operating therein. The casing may be of any ordinary construction and its shape may be varied. It is provided with a rising or upwardly extending leg 1 which will usually be rectangular in cross section in which case the leg will have a front wall 1^a, a rear wall 1^b and side walls. The casing may have a descending leg 2 connected at the top and bottom with the leg 1 by means of a top loop 3 and a bottom loop 4. The bottom loop is provided with an inlet 5 and the upper end of the upwardly extending leg 1 is provided with an outlet 6.

The draft mechanism includes a sprocket wheel 7 located in the top loop, and an endless chain 8 driven by the sprocket. The chain is formed of rigid links 8^a each having a double hinge knuckle 8^b at one end and a single hinge knuckle or eye 8^c at its other end. The eyes 8^c of the links are received in the double knuckles 8^b of adjacent links and are pivotally connected therewith by means of the pins 9. The double knuckles are located at the lower ends of the links 8^a in the rising leg 1 and the lower ends of these knuckles are rounded for engagement by the teeth on the sprocket 7. Preferably two sprockets 7 are employed for engaging both double knuckles 8^b on the links, the latter being positioned between the sprockets.

The chain lies close to the inner or rear wall 1^b of the upwardly extending leg 1 and the links are provided with forwardly extending arms 10 on which flights 11 are pivoted. Preferably the

arms 10 extend from alternate double hinge knuckles 8^b to a point adjacent the front wall 1^a of the leg 1 and each arm is provided with a hinge knuckle 12 adapted to be received between two hinge knuckles 13 on a flight 11. A pintle 14 is passed through each set of knuckles 12, 13. The flights approximately fit the cross-section of the leg 1 and have openings 15 to clear the chain. The rear edge of each flight is adapted to rest on the upper end of the adjacent double hinge knuckle 8^b whereby the flights are adequately supported at their front and rear edges during their passage through the leg 1.

To enable the loads on the flights to be completely cleared into the outlet 6, the flights are tilted seriatim on their pivots 14. This is accomplished by providing suitable means movable relative to the sprockets 7 and chain 8, forming the draft mechanism, for raising the rear edges of the flights. The preferred construction comprises a pair of toothed wheels 16 located at opposite sides of the links 8. The wheels have one or more teeth or projections 17 projecting through slots 18, in the rear wall 1^b of the leg 1, into the path of the flights 11 for engaging the latter seriatim. The wheels 16 are so driven that the peripheral speed of the teeth or projections 17 is greater than the linear speed of the flights to cause the latter to be tilted. The wheels 16 may be secured to a shaft 19 suitably journaled in the casing and this shaft may be driven by sprockets and a chain 20 or gears from the shaft 21 to which the sprockets 7 are secured.

The eye ends of the links 8 carrying the flights are provided with forwardly extending lugs 22 for limiting the swinging movement of the flights as they descend so that each flight will be properly positioned to pick up a fresh load as it nears the inlet 5.

It will be distinctly understood that various modifications may be made without departing from the spirit of my invention.

What I claim as my invention is:

1. A conveyor comprising a casing having an upwardly extending substantially entirely enclosing leg and an outlet; draft mechanism in said casing comprising an endless chain mounted to move longitudinally of the leg; a plurality of conveyor flights pivoted on the chain, each flight approximately fitting the cross-section of the said leg; and movable means for engaging the flights seriatim, the point of engagement of said means with said flights being actuated at a greater speed than that of the draft mechanism;

to cause the flights to be tilted seriatim to a discharging position when the outlet is reached.

2. A conveyer comprising a casing having an upwardly extending substantially entirely enclosing leg and an outlet; draft mechanism in said casing comprising an endless chain mounted to move longitudinally of the leg; a plurality of conveyer flights pivoted on the chain, each flight approximately fitting the cross-section of the said leg; and rotary means including a projection for engaging the flights seriatim, the peripheral speed of the projection being greater than the linear speed of the flights to cause the latter to be tilted to a discharging position when the outlet is reached.

3. A conveyer comprising a casing having an upwardly extending substantially entirely enclosing leg and an outlet; draft mechanism in said casing comprising an endless chain mounted to move longitudinally of the leg; a plurality of forwardly extending arms carried by the chain; conveyer flights pivoted on said arms, each flight approximately fitting the cross section of the said leg; and movable means extending into the leg and into the path of the flights for engaging them seriatim, the point of engagement of said means with said flights being actuated at a greater speed than that of the draft mechanism to cause the flights to be tilted to a discharging position as they reach the outlet.

4. A conveyer comprising a casing having an upwardly extending substantially entirely enclosing leg having a front wall and an outlet; draft mechanism in said casing comprising an endless chain mounted to move longitudinally of the leg, a plurality of arms extending forwardly from the chain to a point adjacent the front wall of the rising leg; conveyer flights pivoted at the forward ends of the arms, each flight approximately fitting the cross section of said leg; and movable means extending into the leg and into the path of the flights for engaging the ends thereof remote from the pivoted ends, the point of engagement of said means with said ends being actuated at a greater speed than that of the draft mechanism to cause the flights to be tilted seriatim to a discharging position as they reach the outlet.

5. A conveyer comprising a casing having an upwardly extending substantially entirely enclosing leg having a front wall and an outlet; draft mechanism in said casing comprising an endless chain mounted to move longitudinally of the leg, a plurality of arms extending forwardly from the chain to a point adjacent the front wall of the rising leg; conveyer flights pivoted at the forward ends of the arms, each flight

approximately fitting the cross section of said leg; and rotary means including a projection extending into the leg and into the path of the flights for engaging the ends thereof remote from the pivoted ends, the peripheral speed of the projection being greater than the linear speed of the flights to cause the latter to be tilted seriatim to a discharging position when the outlet is reached.

6. A conveyer comprising a casing having an upwardly extending substantially entirely enclosing leg having front and rear walls and an outlet; draft mechanism in said casing comprising an endless chain mounted to move longitudinally of the leg, a plurality of arms extending forwardly from the chain to a point adjacent the front wall of the rising leg, conveyer flights pivoted at the forward ends of the arms, each flight approximately fitting the cross section of said leg, the rear wall of the latter having a slot therein; a toothed wheel journaled on the leg and projecting through the slot into the path of the flights for engaging the latter seriatim; and means for driving said wheel so that its peripheral speed will be greater than the linear speed of the flights to cause the latter to be tilted to a discharging position as they reach the outlet.

7. A conveyer comprising a casing having an upwardly extending substantially entirely enclosing leg and an outlet; draft mechanism in said casing comprising an endless chain mounted to move longitudinally of the leg, the chain being provided with rigid links having double hinge knuckles on their lower ends and single hinge knuckles at their upper ends; a double sprocket wheel above the outlet adapted to receive the links between them and to engage the lower ends of the double hinge knuckles; forwardly extending arms on alternate double hinge knuckles; conveyer flights pivoted on said arms, each flight approximately fitting the cross section of said leg and having an opening to clear the chain, the rear edge of each flight being adapted to engage the upper end of the adjacent double hinge knuckle to support said rear edge while the flight is passing through the said leg; and means movable relative to the draft mechanism for raising the rear edges of the flights from the hinge knuckles to cause the flights to be tilted seriatim to a discharging position when the outlet is reached.

8. A conveyer constructed as set forth in claim 7 in which the links are provided with forwardly extending lugs to limit the swinging movement of the flights.

ALBERT FRANCIS WHITE.
